UNITED STATES PATENT OFFICE

2,460,808

TORQUE AMPLIFIER AND REVOLUTION ACCUMULATOR

Benjamin Cooper, Netcong, and Albert F. Hohmann, Teaneck, N. J.; said Hohmann assignor to said Cooper

Application February 14, 1944, Serial No. 522,314

12 Claims. (Cl. 318—8)

1

This invention relates to torque amplifier and revolution accumulator.

An object of the present invention is to provide mechanism for bringing two independently rotating objects into synchronism with each other regardless of whether one gets ahead of the other.

Another object of this invention is to provide a mechanism of the character described, including a rotating or primary shaft and a secondary or follower shaft and means to cause the secondary shaft to follow rotation of the primary shaft, and means to bring the follower shaft into phase with the primary shaft even if the primary shaft gets ahead of the follower shaft, the mechanism also including means to prevent loss of one or more revolutions by the follower shaft in the event that the primary shaft accelerates with sudden rapidity and the follower shaft is unable to follow.

A further object of this invention is to provide a mechanism of the character described having means by which revolutions of the primary or initial rotating body may be stored up or accumulated until the follower catches up so as to bring both into synchronism and including means to amplify the torque of the follower. Thus the initial rotating body may be a weak motor whereas the follower having an amplified torque can operate relatively heavier mechanisms.

Yet a further object of this invention is to provide a mechanism of the character described having a wide variety of uses. Thus said mechanism may be employed in cases where an initial rotating object has a small torque and does not have uniform rotation and where it is desired to rotate a second shaft with an increased torque and through the same angle of rotation as the initial rotating body.

Still a further object of the present invention is to provide a compact apparatus of the character described, which shall be relatively inexpensive to manufacture, easy to assemble, which shall be smooth and positive in operation and yet practical and efficient to a high degree in use.

Other objects of this invention will in part be obvious and in part hereinafter pointed out.

The invention accordingly consists in the features of construction, combinations of elements, and arrangement of parts which will be exemplified in the construction hereinafter described, and of which the scope of application will be indicated in the following claims.

In the accompanying drawing, in which is

2

shown various possible illustrative embodiments of this invention.

Fig. 1 is a top plan view of apparatus embodying the invention;

5 Fig. 2 is a cross-sectional view taken on line 2—2 of Fig. 1;

Fig. 3 is an end view of the apparatus shown in Fig. 2;

10 Fig. 4 is a cross-sectional view taken on line 4—4 of Fig. 2;

Fig. 5 is a cross-sectional view taken on line 5—5 of Fig. 1;

Fig. 6 is a cross-sectional view taken on line 6—6 of Fig. 5;

15 Fig. 7 is a cross-sectional view taken on line 7—7 of Fig. 5;

Fig. 8 is a cross-sectional view taken on line 8—8 of Fig. 5; and

20 Fig. 9 is a wiring diagram of the control circuit.

Referring now in detail to the drawing, 10 designates apparatus embodying the invention. The same comprises a housing or casing 11 having a base 12, a front wall 13, a rear wall 14 and end walls 15 and 16.

25 The end walls are formed with aligned openings 15a and 16a. The front and rear walls are formed with pairs of aligned openings 18 disposed at the same level. Within the openings 15a, 16a are bushings 19 supporting a horizontal shaft 20. On said shaft is a differential mechanism 21. Said differential mechanism comprises a differential body 22. Said body comprises a cylindrical wall 23 and a web 24. The latter is 30 formed with a central opening 25 receiving the shaft 20. The body may be pinned to the shaft as at 26 or otherwise attached thereto. The cylindrical wall 23 is formed with a pair of spaced outwardly extending flanges 28 and 29.

35 Mounted on said cylindrical wall 23 and attached to flange 29 is a gear 30. A portion of the cylindrical wall 23 and part of the web 24 are cut away as shown in Fig. 8 to form a straight surface 32 between the flanges 28, 29 parallel to the axis of shaft 20. Mounted on and between said flanges and projecting into the cut out in the differential body are a pair of parallel shafts 34, 35. On shaft 34 is mounted a gear 36; and on shaft 35 is mounted a gear 37. The gears 36 and 37 have overlapping meshing portions. The teeth of gear 37 are located adjacent flanges 28 and terminate short of flange 29. The teeth of gear 36 are adjacent flange 29 and terminate short of flange 28. It will be noted that shafts 34 and 35 are parallel to shaft 20.

40 45 50 55

Rotatably mounted on shaft 20 and at one side of web 24 is a sleeve 40 formed with a gear 41 meshing with gear 37. Said sleeve is also formed with a worm gear 42 for the purpose hereinafter appearing.

Rotatably mounted on shaft 20 on the opposite side of said web 24 is a sleeve 43 formed with a gear 44 meshing with gear 36. Said sleeve is also formed with a worm gear 45 for the purpose hereinafter appearing. The gears 36 and 37 are similar and the gears 41 and 44 are likewise similar. It will now be understood that if sleeves 40 and 43 rotate in opposite directions at the same rate of speed differential body 22 will remain still. However, if sleeve 40 is rotated faster than sleeve 43 differential body 22 will rotate in one direction.

In the two pairs of openings 18 in the front and rear walls are bearings 50 supporting a pair of parallel horizontal shafts 51 and 52 disposed below shaft 20. On shaft 51 is a worm 53 meshing with worm gear 42; and on shaft 52 is a worm 54 meshing with worm gear 45. At one end of shaft 51 and disposed exteriorly of the casing is a gear 56 meshing with a gear 57 on shaft 58 of a primary rotating object here shown for the purpose of illustration in the form of a motor. On one end of shaft 52 is a follower or secondary rotating object or shaft 60 connected to said shaft 52 by a suitable coupling 61. Connected to the opposite end of shaft 52 by means of coupling 62 is a booster motor 63. This motor 63 is preferably of the reversing type.

If the primary rotates at the same rate of speed as the follower, the differential body 22 will remain stationary. The prime mover often accelerates too rapidly for the follower to follow, thus causing both to be thrown out of phase with each other. Means is therefore provided to make the speed of the primary independent of the speed at which the follower is able to follow; means being further provided by which revolutions of the primary are stored up or accumulated until the follower catches up to it and gets into synchronism or in phase with it. To this end there is fixed to the top of the casing 11 a top plate 65 formed with an opening 66. Fixed to the top plate 65 is a bracket 67 having a flange 68 screwed to said top plate, an end wall 69 extending from said flange, a top wall 70 extending from said end wall, and a pair of parallel downwardly extending vertical walls 72 and 73. Mounted on walls 69 and 73 is a horizontal shaft 74 extending beyond casting 11. Mounted on shaft 74 for rotation is a gear 75 projecting through opening 66 and meshing with gear 30. Fixed to gear 75 for rotation therewith is a wheel 76 provided with a pair of gear teeth 77 forming a gear slot 78 therebetween.

Also rotatably mounted on the shaft 74 adjacent wheel 76 is a gear 79. Fixed to gear 79 for rotation therewith is a wheel 76a similar to wheel 76. There is further mounted on shaft 74 adjacent wheel 76a, a sleeve 80, and fixed to said sleeve is a gear 79a similar to gear 79. Also fixed to said sleeve is a cam 81 comprising a curved part 82 of reduced radius and a curved part 83 of increased radius forming a pair of shoulders 84 and 85 between said portions.

Fixed to end wall 16 of the casing are a pair of normally open switches 90 and 91. Each switch comprises a pair of normally spaced apart switch blades. When the cam 81 is in neutral position as shown in Fig. 3 of the drawing, the switches 90, 91 are open. However, should the cam be rotated either to the right or left, one or the other of the switches 90, 91 will close. The

switches 90 and 91 are connected to the terminals of the booster motor 63 so as to operate said motor when either of the switches are closed, but when both switches are open operation of the motor ceases. When switch 90 closes the motor 63 will rotate in one direction and when switch 91 closes said motor will rotate in an opposite direction.

Supported on and between the walls 69 and 72 is a horizontal shaft 95. Mounted on the shaft 95 are a pair of similar transfer gears 96, 96a. Transfer gear 96 has five teeth 97 adapted to mesh with the teeth 77 of wheel 76 and ten teeth 98 meshing with the teeth of gear 79. Transfer gear 96a is similar to transfer gear 96 and likewise has five teeth adapted to mesh with the teeth of wheel 76a and ten teeth adapted to mesh with the teeth of gear 79a.

The transfer gear serves as a reduction gearing so that it would require a relatively large number of revolutions of gear 30 to rotate cam 81 a complete revolution. This reduction gearing can be multiplied so as to make it impossible to rotate cam 81 through a complete revolution under practical conditions, thereby making it impossible for the transmitter to lose one or more complete revolutions.

It will be noted that an initial angular rotation of gear 75 is transferred to cam 81 without appreciable change, when said cam is in normal position. However as soon as the cam is out of normal position, and one of the switches 90, 91 is closed, one thousand revolutions are required to cause a complete revolution of the cam. If straight reduction gearing were used rotation of gear 75 would at all times cause cam 81 to rotate one-one thousandth of the angle of movement of said gear 75. With such straight reduction gearing it would not be possible to obtain quick closure of one of the switches 90, 91 and yet prevent loss of a revolution of cam 81.

The operation of the device will now be understood. As the primary rotates, it will rotate the differential body causing rotation of the cam 81 which will thereby energize the motor 63 and cause the follower to be rotated and to follow the primary. The follower will rotate through the same angle as the primary to rotate the cam back toward neutral position. The booster motor will remain energized until the follower becomes synchronous with the primary. Should the primary become accelerated too rapidly for the follower to follow, the follower will continue rotating after the primary stops, until the follower catches up. Rotations or revolutions of the primary are thus stored up until the follower catches up to the primary.

Furthermore the torque of the follower is greater than the primary because of the booster motor which is selected to have a greater torque than the primary motor 59.

Furthermore it is not impossible for the follower to lose a complete revolution then get into phase with the primary but a revolution behind, because the reduction gearing takes care of the greatest possible acceleration of the follower under working conditions.

It will be noted that the secondary will follow the primary in either direction because of the provision of the reversing motor 63 and the switches 90, 91 either one or the other of which will be closed by the cam depending upon direction of rotation of the cam.

It will be noted that the motor 59 and the motor 63 with their connections to the sleeves 40

and 45 comprise the inputs for the differential mechanism, whereas the output for operating the reversing switch, is taken from the body 21 and gear 30. Thus there is provided means controlled by the output of the differential mechanism to bring the inputs in phase.

In Fig. 9 there is shown a wiring diagram of the circuit control for motor 63. In said diagram there is shown cam 81 controlling switches 90, 91. Switch 90 comprises contacts 90a, 90b. Switch 91 comprises contacts 91a, 91b. Contacts 90a, 91a are connected to one side 100 of the power supply.

Motor 63 has a field coil 101 and an armature 102. There is employed in the circuit a pair of relays 103, 104. Relay 103 controls a 2 pole normally open switch 105 comprising fixed contacts 106, 107 and movable switch arms 106a, 107a respectively. Relay 104 controls a 2 pole normally open switch 108 comprising fixed contacts 109, 110 and movable switch arms 109a, 110a respectively. Fixed contacts 107, 110 are interconnected by wire 111 and are connected one armature brush by wire 112. Contacts 106, 109 are interconnected by wire 113 and are connected to the other armature brush by wire 114. Switch arms 107a, 109a are interconnected by wire 115, and are connected to one side of field coil 101 by wire 115a. Switch arms 106a, 110a are connected to feed line 100 by wires 116, 117 respectively. Relay coil 103 is connected on one side by wire 118 to contact 90b. Relay coil 104 is connected on one side to switch contact 91b by wire 119. The other sides of relay coils 103, 104 are interconnected by wire 120, and are connected to the other side of the field coil 101 by wire 120a. Said other side of the field coil 101 is connected by wire 121 to power feed line 122.

The circuit described above is a typical motor reversing circuit.

When cam 81 is in normal or neutral position, switches 90, 91 are both open and the motor is stationary. Upon rotating cam 81 in a clockwise direction looking at Fig. 9, switch 90 closes and switch 91 remains open. Relay 103 is energized to cause rotation of the motor in one direction. Should cam 81 be rotated from normal or neutral position in a counterclockwise direction, relay 104 is energized and the motor is rotated in a reverse direction.

It will thus be seen that there is provided a device in which the several objects of this invention are achieved, and which is well adapted to meet the conditions of practical use.

As various possible embodiments might be made of the above invention, and as various changes might be made in the embodiments above set forth, it is to be understood that all matter herein set forth or shown in the accompanying drawing is to be interpreted as illustrative and not in a limiting sense.

Having thus described our invention, we claim as new and desire to secure by Letters Patent:

1. In combination, a differential mechanism, a pair of inputs for said mechanism, an output for said differential mechanism, means controlled by the output to keep the two inputs in phase, said means including a cam, a pair of switches controlled by said cam, said switches being open when said cam is in normal position, said cam having means to close one switch while leaving the other switch open when said cam is rotated away from normal position in one direction, and for closing said other switch while leaving the first switch open when said cam is rotated away

from normal position in an opposite direction, a reversing motor connected to one of said inputs, means controlled by said switches to rotate said motor in one direction when said cam is rotated in one direction and for reversing the motor when said cam is rotated in an opposite direction and for deenergizing said motor when said cam is in normal position, and transfer means connecting said output with said cam.

2. In combination, a differential mechanism, a pair of inputs therefor and an output therefor, an electric motor connected to one of the inputs, means actuated by the output to operate said motor to bring the input to which the motor is connected into phase with the other input, and including a rotary member, a circuit controlling the motor and including means controlled by rotation of said rotary member, and means interconnecting said output with said rotary member for rotating said rotary member through one revolution for a multiple of revolutions of said output.

3. A differential having a pair of inputs and an output, means to rotate one input, an electric motor to operate the other input, a cam, switch means controlled by said cam to energize said motor, and means controlled by said output to rotate said cam, said last means including means interposed between said output and said cam to cause said cam to be rotated through a lesser angle than said output.

4. In combination, differential mechanism comprising a pair of inputs and an output, means including an electric motor to rotate one of said inputs, means controlled by said output to control the operation of said motor, said last means comprising a cam, transfer gearing connecting said output with said cam, said transfer gearing being so arranged that when the cam is in normal position, initial movement of said output will cause initial movement of said cam away from normal and continued movement of said output in the same direction will result in alternating non-movement and movement of said cam, and switch means controlled by the cam for energizing said motor.

5. In combination, a shaft, differential mechanism comprising a differential body on said shaft, a pair of gears rotatably mounted on said body and disposed parallel to said shaft, said gears meshing with each other, a pair of gears on said shaft meshing with the first pair of gears, respectively, an electric motor to rotate one of said second pair of gears, means controlled by said body to control the operation of said motor, said last means comprising a gear on said body, a second shaft, a cam on said second shaft, transfer gearing connecting the gear on said body with said cam, said transfer gearing being so arranged that when the cam is in normal position, initial movement of said output will cause initial movement of said cam away from normal and continued movement of said output in the same direction will result in alternating non-movement and movement of said cam, and switch means controlled by the cam for energizing said motor.

6. In combination, differential mechanism comprising a pair of inputs and an output, an electric motor to rotate one of said inputs, a second electric motor to rotate the other of said inputs, means controlled by said output to control the operation of said second motor, said last means comprising a cam, transfer gearing connecting said output with said cam, said transfer

gearing being so arranged that when the cam is in normal position, initial movement of said output will cause initial movement of said cam away from normal and continued movement of said output in the same direction will result in alternating non-movement and movement of said cam, switch means controlled by the cam for energizing said second motor, said second motor having a greater torque than said first motor.

7. In combination, a differential having a pair of inputs and an output, means to rotate one input in either direction, a reversing electric motor connected to rotate the other input, a cam, means controlled by said output to rotate said cam, a pair of switches controlled by said cam, one switch being connected to the electric motor to operate said motor in one direction when said switch is actuated, and the other switch connected to said electric motor to operate said motor in a reverse direction when said second switch is actuated, said switches being normally in unactuated condition when the inputs are in phase, and said cam being adapted to actuate one of the switches while permitting said other switch to remain unactuated when said cam is rotated in one direction, and to actuate the second switch while permitting the first switch to remain unactuated upon rotating said cam in an opposite direction, and reduction gearing interposed between said output and said cam.

8. In combination, a motor, a differential having a pair of inputs and an output, said motor being connected to one of the inputs of said differential, a second motor connected to the other input of said differential, means controlled by the output of said differential for operating said second motor, said means including switch means to control the operation of said second motor, cam means actuated by the output and controlling the actuation of said switch, and speed reducing means interposed between said output and cam.

9. In combination, a differential having a pair of inputs and an output, means to rotate one input in either direction, a reversing electric motor connected to rotate the other input, a cam, means controlled by said output to rotate said cam, a pair of switches controlled by said cam, one switch being connected to the electric motor to operate said motor in one direction when said switch is actuated, and the other switch connected to said electric motor to operate said motor in a reverse direction when said second switch is actuated, said switches being normally in unactuated condition when the inputs are in phase, and said cam being adapted to actuate one of the switches while permitting said other switch to remain unactuated when said cam is rotated in one direction, and to actuate the second switch while permitting the first switch to remain unactuated upon rotating said cam in an opposite direction and transfer gearing interposed between said output and said cam, said transfer gearing being so arranged that when the cam is in normal position, initial movement of said output will cause initial movement of said cam away from normal and continued movement of said output in the same direction will result in alternating non-movement and movement of said cam.

10. In combination, a motor, a differential having a pair of inputs and an output, said motor being connected to one of the inputs of said

differential, a second motor connected to the other input of said differential, means controlled by the output of said differential for operating said second motor, said means including switch means to control the operation of said second motor, cam means actuated by the output and controlling the actuation of said switch, and speed reducing transfer gearing interposed between said output and cam, said transfer gearing being so arranged that when the cam is in normal position, initial movement of said output will cause initial movement of said cam away from normal and continued movement of said output in the same direction will result in alternating non-movement and movement of said cam.

11. In combination, a differential mechanism, a pair of inputs for said mechanism, an output for said differential mechanism, means controlled by the output to keep the two inputs in phase, said means including a cam, a pair of switches controlled by said cam, said switches being open when said cam is in normal position, said cam having means to close one switch while leaving the other switch open when said cam is rotated away from normal position in an opposite direction, a reversing motor connected to one of said inputs, means controlled by said switches to rotate said motor in one direction when said cam is rotated in one direction and for reversing the motor when said cam is rotated in an opposite direction and for deenergizing said motor when said cam is normal position, and transfer gearing connecting said output with said cam, said transfer gearing being so arranged that when the cam is in normal position, initial movement of said output will cause initial movement of said cam away from normal and continued movement of said output in the same direction will result in alternating non-movement and movement of said cam.

12. In combination, a differential mechanism, a pair of inputs therefor and an output therefor, an electric motor connected to one of the inputs, means actuated by the output to cause said motor to bring the input to which the motor is connected into phase with the other input, and including a rotary member, a circuit controlling the motor and including means controlled by rotation of said rotary member, and means interconnecting said output with said rotary member for rotating said rotary member through one revolution for a multiple of revolutions of said output, the interconnecting means being so arranged that when said rotary member is in normal position, initial movement of said output will result in initial movement of said rotary member away from normal, whereas continued movement of said output will cause alternating non-movement and movement of said rotary member.
